UNITED STATES PATENT OFFICE

148,168

DESIGN FOR AN ASH TRAY

Nubar A. Karakashian, Philadelphia, Pa.

Application July 1, 1946, Serial No. 131,224

Term of patent 3½ years

(Cl. D85—2)

To all whom it may concern:

Be it known that I, Nubar A. Karakashian, a citizen of the United States, residing at Philadelphia, in the county of Philadelphia and State of Pennsylvania, have invented a new, original, and ornamental Design for an Ash Tray, of which the following is a specification, reference being had to the accompanying drawing, forming part thereof.

Figure 1 is a top plan view of an ash tray, showing my new design.

Figure 2 is a cross sectional view, taken substantially in the plane of the line 2—2 in Figure 1, and

Figure 3 is a front view of the ash tray shown in Figures 1 and 2.

I claim:

The ornamental design for an ash tray, as shown.

NUBAR A. KARAKASHIAN.
